MACHINE OR APPARATUS FOR THREADING
BUTTONS ON TO A WIRE OR WIRES OR
THE EQUIVALENT

Vincent Joseph Clarkson, Leeds, England

Application March 31, 1934, Serial No. 718,527
In Great Britain April 6, 1933

11 Claims. (Cl. 29—84)

This invention relates to machines or apparatus for threading buttons on to a wire or wires or the equivalent more particularly for packing purposes, said wire or wires or the equivalent being substantially rigid and adapted to serve as a button holding device or to constitute a guide or guides for delivering the buttons on to a flexible wire or wires or the equivalent.

According to the invention the buttons are fed singly into a pocket or die, the base of which is constituted by the upper one of two sets or pairs of superposed slides or shutters which alternately co-operate with the upper end or ends of the substantially rigid wire or wires or the equivalent to retain it or them in position to receive the buttons from said pocket or die. The arrangement would preferably be such that only one set or pair of slides or shutters is open at a time, and during each closed period of the upper set or pair of slides or shutters the button supported thereby would be correctly located or positioned with one or more of its holes in register with the upper end or ends of the substantially rigid wire or wires ready to be dropped thereonto when said upper shutters are opened. In this connection each button when in the pocket or die may be correctly located or positioned with respect to the upper end or ends of the substantially rigid wire or wires by means of a rotary positioning head of the kind having pins which engage the holes in the button and rotate the latter so as to bring said holes into predetermined positions.

In order that the invention may be clearly understood and readily carried into effect, the same will now be more fully described with reference to and by the aid of the embodiment illustrated in the accompanying drawings; wherein:—

Figures 1, 2 and 3 are respectively a front elevation, plan and part inverted plan of the button threading apparatus.

Figure 4 is a fragmentary view illustrating the threading of buttons on to a button holder of rigid wire.

Figure 5 illustrates in a similar fragmentary view the threading of buttons on to flexible wires.

Figure 6 is a front elevation of the rotary button hopper associated with the upper end of the chute which feeds the buttons to the threading apparatus.

Referring to the drawings, the buttons 1 are delivered from a rotary hopper 2 and associated circular fence 3 by way of a pivoted and spring-controlled outlet gate 3^x to a chute 4 which delivers the said buttons 1 in turn each into one of an annular series of circular holes 5 afforded in

a ratchet ring 6 working upon the base plate or table 7 of the apparatus about a centre bearing piece 8. The ratchet ring 6 is intermittently actuated by a pawl 9 and spring-connected lever 10 which is operated by a cam 11 on a cam shaft 12 below the table 7, said shaft 12 being mounted in bearings 13 and driven through the medium of a pulley 14. In this way the ring 6 is moved round step by step to bring the buttons 1 in turn into register with a pocket or die 15 at the threading position in the table 7, and the lever 10 with its pawl 9 is returned ready for each successive stroke by means of a lever 16 operated by a cam 17 on the shaft 12 and pivoted in a bracket 18 fixed to the underside of the table 7, said lever 16 projecting upwardly through a hole at 19 formed through the table 7 and centre piece bearing 8.

The base of the pocket or die 15 is afforded by an upper pair of shutters 20 slidable toward and away from each other in guides 21 secured to the underside of the table 7, and said upper pair of shutters 20, which are adapted to grip or engage the upper ends of a rigid wire or rigid wires 22 flush with their upper surface, are engaged through pin and slot mechanisms 23 with operating levers 24 which are connected together by a link 25 and positively operated against the action of a spring 26 by means of a cam 27 on the shaft 12 engaging a depending portion of one of said levers 24.

At a short distance below the shutters 20 is carried on depending studs 28 a guide 29 for a lower pair of shutters 30 which are also adapted to grip or co-operate with the wire or wires 22 and to be operated in similar manner to the upper pair of shutters 20 by means of pin and slot mechanisms 31, levers 32, link 33, and a cam 34 on the shaft 12 against the action of a spring 35.

At or above the threading position is a rotatable head 36 having depending pins for engaging the holes in the button in the pocket or die 15, and said head 36 is rotatably carried in the free end of a lever 37 pivoted in a bracket 38 on the upper side of the table 7 and operated, against the action of a spring 39 connecting it to the table 7, by means of a cam 40 on the shaft 12 operating through the hole 19, said lever 37 being guided vertically by brackets 41 fixed to the centre piece 8. The shaft 42 of the head 36 projects through the free end of the lever 37 and has fixed on its upper end a crosshead 43 one end of which is connected by a spring 44 to the lever 37 at its pivot end, and the other end of

5

20

25

30

40

45

50

55

said crosshead 43 is connected by a link 45 to the upper end of the lever 16.

The cam shaft 12 is fitted with a loose pulley 46 in addition to the fixed driving pulley 14, 5 whilst an anchored leaf spring 47 on the table 7 rides over and snaps into the teeth of the ratchet ring 6 at each operation to prevent any return movement of said ring 6.

In Figure 4 the button holder is in the form 10 of a rigid wire 22 bent upon itself in the form of a U, the bottom or bend of the U-shaped wire holder being supported in a cup-shaped depression or slot in a fixed block 48 the requisite distance below the upper shutters 20.

15 In Figure 5 a pair of rigid wires 22 are mounted in parallel relationship in a block or supporting clamp 49 which also serves as a stop for the buttons 1 received thereon in pile formation, and said wires 22 have eyes at 50 through which are 20 threaded the opposite ends of a fine flexible wire, cotton, or thread 51 upon which the pile of buttons 1 collected on the wires above the stop 49 can be allowed to fall upon removing the said stop 49. In this connection once the pile of buttons 25 1 has been dropped on to the wire or the like 51, the stop can be immediately re-applied to the wires 22 so that threading and piling up of buttons 1 can proceed whilst the wire or the like 51 is removed from the eyes 50 and its ends tied 30 together to secure the buttons 1 which have been received thereon. Instead of eyes, hooked ends may be employed.

Assuming the parts to be in the positions shown 35 in Figures 1 and 2 with both pairs of shutters 20 and 30 closed or together and a button 1 resting upon the upper pair of shutters 20 in the pocket or die 15 and also one threaded upon the upper ends of the wire or wires 22 and resting upon the bottom pair of shutters 30, the rotary head 40 36 descends upon the button 1 in the pocket or die 15 through the action of the cam 40 allowing the spring 39 to pull the lever 37 down so that the head bears resiliently upon the button 1 in the die 15. During the descent of the head 36, the cam 34 operates the lower pair of shutters 30 so as to move them apart (as shown in Figure 3) to allow the button 1 resting upon said shutters 30 to fall down the wire or wires 22 on to the pile already threaded thereon. During 45 the continued rotation of the cam shaft 12 the lower pair of shutters 30 close under the action of their spring 35 so as to again grip or co-operate with the wire or wires 22, and whilst this is taking place the head 36 is rotated by the cam 17, lever 16, and link 45, so as to cause 50 its pins to engage or snap into the holes in the button 1 in the pocket or die 15, under the action of the spring 39, and rotate said button 1 to a predetermined position in which certain of its 55 holes are in register with the ends of the wire or wires 22 below. During the rotation of the head 36 to position the button 1 in the pocket or die 15 in relation to the wire or wires 22, the lever 16 operates the pawl lever 10 so as to bring the 60 pawl into engagement with the next tooth of the ratchet ring 6 ready for the next feeding operation. Further continued rotation of the cam shaft 12 causes the cam 27 to open or move apart the upper pair of shutters 20 so as to allow the button 1 in the pocket or die 15 to fall over the ends of the wire or wires 22 and down on to the bottom pair of shutters 30.

When the upper pair of shutters 20 have moved 70 apart the cam 40 raises the lever 37 to lift the head 36 clear of the ring 6, whereupon the cam

11 operates the lever 10 and pawl 9 to rotate the ratchet ring 6 another step and bring another button 1 into the pocket or die 15. During this movement the spring 44 comes into action to return or rotate the head 36 into its original position. This completes the cycle of operations which takes place every complete revolution of the cam shaft 12.

When U-shaped button holders are employed 10 these would be removed and substituted as they became loaded with the requisite number of buttons, the machine or apparatus being stopped during the changing of the holders. Where flexible wires are employed as holders and the rigid wires 22 serve merely as guides, the machine or 15 apparatus may be run continuously.

The chute 4 may have associated therewith an intermittently actuated control gate whereby the button supply is regulated in accordance with the operation of the rotary positioning head, 20 or the button feed may be effected by gravity only as shown.

Machines or apparatus as above described may be arranged in a battery or bank side by side and may be operated from a common power driven 25 shaft, and one feed hopper may supply two or more machines, whilst the whole battery of say four or six machines may be under the care of a single operative. In this connection the operative's duties would be to remove the wires loaded 30 with buttons and to substitute therefor fresh wires for loading.

It will be seen that the present invention provides a simple and economical method of and means for threading buttons on wires or the 35 equivalent as compared with hand methods hitherto employed.

I claim:—

1. A machine or apparatus for threading buttons on to a wire or wires or the equivalent, 40 wherein the buttons are fed singly into a pocket or die the base of which is constituted by the upper one of two sets or pairs of superposed slides or shutters which alternately co-operate with the upper end or ends of the wire or wires or the 45 equivalent to retain it or them in position to receive the buttons from said pocket or die.

2. A machine or apparatus according to claim 1, wherein only one set or pair of shutters is open 50 at a time, and during each closed period of the upper set or pair of shutters the button supported thereby is correctly located or positioned with certain of its holes in register with the upper end or ends of the substantially rigid wire or wires or the equivalent ready to be dropped 55 thereonto when said shutters are opened.

3. A machine or apparatus for threading buttons on to a wire or wires or the equivalent, 60 wherein the buttons are fed singly into a pocket or die the base of which is constituted by the upper one of two sets or pairs of superposed slides or shutters which alternately co-operate with the upper end or ends of the wire or wires or the 65 equivalent to retain it or them in position to receive the buttons from said pocket or die, only one set or pair of shutters being open at a time, and during each closed period of the upper set or pair of shutters the button supported thereby is correctly located or positioned with certain of its holes in register with the upper end or ends of the substantially rigid wire or wires or the equivalent ready to be dropped 70 thereonto when said shutters are opened, each button when in the pocket or die being correctly located or positioned with respect to the upper end or ends of 75

the substantially rigid wire or wires or the equivalent by means of a rotary positioning head of the kind having pins which engage the holes in the button and rotate the latter so as to bring 5 said holes into predetermined positions in register with the substantially rigid wire or wires or the equivalent engaged or gripped between the upper shutters.

4. A machine or apparatus according to claim 10 3, wherein the substantially rigid wire or wires or the equivalent is or are adapted to serve as a button holder.

5. A machine or apparatus according to claim 3, wherein the substantially rigid wire or wires or the equivalent are adapted to serve as guides down which the buttons fall so as to be threaded on to a flexible wire or wires or the equivalent.

6. A machine or apparatus for threading buttons on to a wire or wires or the equivalent, where- 20 in the buttons are fed singly into a pocket or die the base of which is constituted by the upper one of two sets or pairs of superposed slides or shutters which alternately cooperate with the upper end or ends of the wire or wires or the equivalent 25 to retain it or them in position to receive the buttons from said pocket or die, only one set or pair of shutters being open at a time, and during each closed period of the upper set or pair of shutters the button supported thereby is correctly 30 located or positioned with certain of its holes in register with the upper end or ends of the substantially rigid wire or wires or the equivalent 35 ready to be dropped thereonto when said shutters are opened, each button when in the pocket or die being correctly located or positioned with respect to the upper end or ends of the substantially rigid wire or wires or the equivalent by means of a rotary positioning head of the kind having pins which engage the holes in the button and rotate 40 the latter so as to bring said holes into predeter- 45 mined positions in register with the substantially rigid wire or wires or the equivalent engaged or gripped between the upper shutters, the substantially rigid wire or wires or the equivalent being adapted to serve as guides down which the but- 50 tons fall so as to be threaded onto a flexible wire or wires or the equivalent, the substantially rigid wire or wires or the equivalent being formed with eyes for attachment of the flexible wire or wires or the equivalent.

7. A machine or apparatus for threading buttons on to a wire or wires or the equivalent, where- 55 in the buttons are fed singly into a pocket or die the base of which is constituted by the upper one of two sets or pairs of superposed slides or shutters which alternately cooperate with the upper end or ends of the wire or wires or the equivalent 60 to retain it or them in position to receive the buttons from said pocket or die, only one set or pair of shutters being open at a time, and during each closed period of the upper set or pair of shutters the button supported thereby is correctly 65 located or positioned with certain of its holes in register with the upper end or ends of the substantially rigid wire or wires or the equivalent 70 ready to be dropped thereonto when said shutters are opened, the shutters being operated or opened against the action of springs through the medium of cam-actuated lever mechanisms arranged to operate said shutters alternately and to give the necessary rest periods or dwells to allow for sup- 75 porting of the buttons upon the shutters during the hole positioning operation.

8. A machine or apparatus according to claim 7, wherein the positioning head is rotated by a cam-actuated lever and link mechanism, and in which said positioning head is carried by a lever which is raised intermittently by a cam against the action of a spring. 5

9. A machine or apparatus according to claim 7, wherein the buttons are fed in turn to the pocket or die by means of a cam ratchet wheel operated by a cam-actuated lever and pawl. 10

10. A machine or apparatus for threading buttons on to a wire or wires or the equivalent, where- 15 in the buttons are fed singly into a pocket or die the base of which is constituted by the upper one of two sets or pairs of superposed slides or shutters which alternately cooperate with the upper end or ends of the wire or wires or the equivalent 20 to retain it or them in position to receive the buttons from said pocket or die, only one set or pair of shutters being open at a time, and during each closed period of the upper set or pair of shutters the button supported thereby is correctly 25 located or positioned with certain of its holes in register with the upper end or ends of the substantially rigid wire or wires or the equivalent 30 ready to be dropped thereonto when said shutters are opened, the shutters being operated or opened against the action of springs through the medium of cam actuated lever mechanisms arranged to operate said shutters alternately and to give the necessary rest periods or dwells to allow for sup- 35 porting of the buttons upon the shutters during the hole positioning operation, the positioning head being rotated by a cam-actuated lever and link mechanism, said positioning head being carried by a lever which is raised intermittently by a cam against the action of a spring, the buttons being fed in turn to the pocket or die by means of a cam ratchet wheel operated by a cam actuated lever and pawl, all the cams being mounted upon 40 a common shaft.

11. A machine or apparatus for threading buttons on to a wire or wires or the equivalent, where- 45 in the buttons are fed singly into a pocket or die the base of which is constituted by the upper one of two sets or pairs of superposed slides or shutters which alternately cooperate with the upper end or ends of the wire or wires or the equivalent 50 to retain it or them in position to receive the buttons from said pocket or die, only one set or pair of shutters being open at a time, and during each closed period of the upper set or pair of shutters the button supported thereby is correctly located or positioned with certain of its holes in register with the upper end or ends of the substantially rigid wire or wires or the equivalent 55 ready to be dropped thereonto when said shutters are opened, the shutters being operated or opened against the action of springs through the medium of cam-actuated lever mechanisms arranged to operate said shutters alternately and to give the necessary rest periods or dwells to allow for supporting of the buttons upon the shutters during the hole positioning operation, the buttons being fed in turn 60 to the pocket or die by means of a cam ratchet wheel operated by a cam-actuated lever and pawl, the buttons being fed to the ratchet wheel by a chute from a rotary feed hopper having an associated spring controlled gate to regulate the but- 65 ton supply. 70

VINCENT JOSEPH CLARKSON.
